UNITED STATES PATENT OFFICE

2,600,026

ELECTRICAL COIN DISPENSER

Levi Schlabach, Sr., Delaware, Ohio

Application July 14, 1948, Serial No. 38,619

4 Claims. (Cl. 133—5)

1

This invention relates to new and useful improvements in coin dispensers, and the primary object of the present invention is to provide an electrical dispenser for vehicles which is operatively connected to the ignition switch of a vehicle and which will operate to effectively expel or discharge a coin therefrom only when the ignition switch has been actuated by an operator.

Another important object of the present invention is to provide a coin dispenser for vehicles and the like that will permit a driver to have at his disposal coins for toll bridges, parking meters and the like and which is conveniently actuated by a user.

A further object of the present invention is to provide an electrical coin dispenser including a slide, and embodying novel and improved locking means for holding said slide against sliding movement and for releasing said locking means.

A still further aim of the present invention is to provide an electrical coin dispenser that is simple and practical in construction, strong and reliable in use, neat and attractive in appearance, small and compact in structure, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the electrical coin dispenser constructed in accordance with the present invention;

Figure 2 is a longitudinal vertical sectional view of Figure 1, showing the slide disposed within the casing, and with dotted lines showing the slide disposed outwardly of the casing for discharging a coin therefrom;

Figure 3 is a transverse vertical sectional view taken substantially on the plane of section line 3—3 of Figure 2;

Figure 4 is a longitudinal horizontal sectional view taken substantially on the plane of section line 4—4 of Figure 2;

Figure 5 is a perspective view of the slide used in conjunction with the present invention, and with parts broken away and shown in section; and

Figure 6 is a perspective view of the pivotal locking member used in conjunction with the present invention.

2

Referring now to the drawings in detail, wherein for the purpose of illustration, there is disclosed a preferred embodiment of the present invention, the numeral 10 represents a housing or casing of any suitable size, shape or material generally, and which preferably includes a bottom wall 12, a forward rounded or arcuate end wall 14, a rear flat end wall 16, a flat upper wall 20, and side walls 22.

10 A coin compartment or sleeve 24 is fixed in the casing 10, against the inner periphery of the forward wall 14, and communicates with a coin slot 26 provided in the upper wall 20. The lower open end 28 of the coin compartment 15 24 is spaced above the bottom wall 12 and lies in a plane with the upper edge of an arcuate, substantially rectangular slot or guide opening 30 provided in the forward wall 14, adjacent the bottom wall 12.

15 Slidably positioned on the inner face of the bottom wall 12, and movable into and out of the casing 10 through the opening 30, is a substantially rectangular slide or guide 32 having an arcuate or rounded outer edge 34. A recess 20 or coin receiving opening 36 is provided in the forward end of slide 32, and a pair of spaced parallel, lateral arms or straps 38 are integrally formed at the rear edge of the slide 32 to engage the compartment 24 and thus limit the outward 25 sliding movement of the slide 32.

20 Receivably engaging an internally threaded opening 40 provided in the slide 32, adjacent the stops 38, is the externally threaded portion 42 of a depending hollow member or sleeve 44 having a head portion 46 that slidably engages a longitudinal guide slot 48 provided in the bottom wall 12 and an annular bearing shoulder 50 that bears upon the outer surface of the bottom wall 12.

25 A shank or shaft 52 extends through the sleeve 40 and is integrally formed with a bearing element or cam 54 having a convexed bearing surface for a purpose which will later be more fully apparent.

The lower end 56 of the shank 52 is externally threaded to receivably engage an internally threaded aperture 58 provided in a cap or grip 60 that embraces the lower end of the shank 52, and a coil spring 62 embraces the shank 52 and is biased between the outer end of the sleeve 44 and the cap 60 to normally urge the shank 52 outwardly to cause the cam 54 to bear upon the top of slide 32. The outer surface of the cap 60 is knurled to provide a finger-engaging surface.

Suitably fixed within the housing and to one side wall thereof, is a transversely extending bear-

ing sleeve 64 that receives a transverse pivot pin 66 which also engages a knuckle or sleeve 68 at one edge of a pivotal locking member or substantially rectangular plate 70 of magnetizable material.

The rear transverse edge of the locking member 10 is centrally notched as at 12 to provide a pair of projections or bearing lugs 74 having lips 75 that normally bear upon the upper edges of the projections or stops 38 when the slide 32 is disposed within the casing 10.

An angular substantially L-shaped spring member 76 is fixed at one leg to the inner face of the rear wall 16, and the free leg thereof bears upon the locking member 70 to urge the same into normal locking engagement with the stops 38, thus preventing sliding movement of the slide 32.

Suitably mounted in the casing 10 and on the rear wall 16, is a pair of electro-magnets 78 having cores 80 which are normally spaced from the locking member 70 and on either side of the spring 76.

Fixed by a rivet or the like 82 to the rear wall 16 of the casing 10, is the angulated-end portion 84 of a substantially L-shaped fixed conductive member 86 that is connected by wires 88 to the electro-magnets 78. It being understood that the electro-magnets 78 are connected by a further wire 90 to one terminal of a vehicle-ignition switch or such other suitable source of electric current.

The free end of the member 86 is insulated from and secured to a movable conductive member 92 by an insulated spacer block 94, and the free end of the member 92 supports a contact tip or element 96 that is normally spaced from a further contact tip or element 98 carried by member 86.

The member 92 is suitably connected to a source of electric current, preferably the ignition switch of a vehicle so that the members 86 and 92 will function as a switch controlling the electro-magnets 78.

It should be noted that the angulated end 84 of the member 86 is also insulated by a strip 99 from the rear wall 16 of the casing 10.

The casing 10 is removably supported relative to the dashboard of a vehicle or to a supporting structural element by brackets or the like 100.

In practical use of the present invention, as electrically connected to the circuit system of a vehicle and more particularly the ignition switch of a vehicle, so that as the ignition switch is actuated by an operator to an "on" position, current may flow to the electro-magnets 78 and the movable conductive member 92. The slide 32 is disposed within the casing, and, therefore, the cam 54 urges the tip 96 into circuit closing position with the tip 98 when the grip 60 is raised and the coils or electro-magnets 78 will become energized to raise or pivot the locking member 70 upwardly, thus disengaging the projections 74 thereof from the stops 38, and the slide 32 may be moved outwardly from the casing 10. As the slide 32 is moved outwardly by the finger-grip 60, a coin engaged in the opening 36 will be discharged from the said slide into the hand of a user which is disposed beneath the same.

Obviously, as the slide 32 is moved outwardly from the casing and pressure on grip 60 is released, the cam 54 will disengage the movable conductive member 92, thus breaking the circuit and permitting the locking member 70 to pivot downwardly and rest upon the upper edges of the stops 38 until such time as the slide 32 is again

pushed into the casing to complete the circuit and raise the locking member.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. An electric coin dispenser comprising a casing having a coin compartment, a horizontally disposed flat slide carried by said casing for movement into and out of said casing, said slide having a coin-receiving recess for engaging a coin in said compartment upon inward sliding movement of said slide, said slide having a lateral upstanding projection forming a stop for engaging the compartment to limit the outward sliding movement of said slide, a pivotal locking member carried by said casing engageable with said projection to hold said slide against sliding movement, means normally urging said locking member into locking engagement with said projection, an electro-magnet overlying said locking member connected to a source of current for releasing said locking member from said projection, a switch controlling said electro-magnet and overlying said slide, said switch including a fixed conductive member and a movable conductive member, a sleeve secured to the slide, said casing including a lower wall having a slot receiving the sleeve, and means slidably carried by said sleeve and movable laterally of said slide for actuating said conductive members into circuit closing engagement.

2. An electric coin dispenser comprising a casing having a coin compartment, a horizontally disposed flat slide carried by said casing for movement into and out of said casing, said slide having a coin receiving recess for engaging a coin in said compartment upon inward sliding movement of said slide, said slide having a lateral upstanding projection forming a stop for engaging the compartment to limit the outward sliding movement of said slide, a pivotal locking member carried by said casing engageable with said projection to hold said slide against sliding movement, means normally urging said locking member into locking engagement with said projection, an electro-magnet overlying said locking member connected to a source of current for releasing said locking member from said projection, a switch mounted within said casing and controlling said electro-magnet, said switch overlying said slide and including a fixed conductive member and a movable conductive member, said conductive members being disposed entirely within said casing, a sleeve secured to and disposed perpendicular of said slide, said casing including a lower wall having a slot receiving the sleeve, and means slidably carried by said sleeve and movable laterally of said slide for actuating said conductive members into circuit closing engagement, said movable conductive member overlying said last named means, said means slidably carried by said sleeve for actuating said conductive members into circuit closing engagement, includes a shaft received in said sleeve and hav-

ing first and second end portions, a cam secured to the first end portions of said shaft and disposed within said casing for engaging and forcing the movable conductive member into circuit closing position with said fixed conductive member, a cap threaded to the second end portion of said shaft, and a spring member embracing said shaft and biased between one end of said sleeve and said cap to urge the cam toward the slide, said cap being manually moved against the force of the spring to cause the cam to force the movable conductive member into circuit closing position with said fixed conductive member.

3. A coin dispenser comprising a casing including a bottom wall, said casing having a horizontal opening over the bottom wall, a flat slide member slidably supported on said bottom wall and movable into and out of said casing through said opening, said member including a coin receiving opening, a coin compartment in said casing having an open bottom overlying the slide member and in registry with said coin receiving opening when the slide member is disposed within the casing, said slide member including a bifurcated end, each furcation of said bifurcated end having a lateral projection, a swingable locking member in said casing overlying said slide member and engaging said projections to lock the slide member against sliding movement, electric means carried by said casing for raising the locking member away from the projection to permit sliding movement of the slide member, a switch connected to said electric means supported by and within said casing and disposed between said projections and above said slide member, and means carried by and movable with said slide member and slidable laterally of said slide member for engaging and actuating said switch, said bottom wall having a slot receiving said last named means.

4. A coin dispenser comprising a casing including a bottom wall, said casing having a horizontal opening over the bottom wall, a flat slide member slidably supported on said bottom wall and movable into and out of said casing through said opening, said member including a coin receiving opening, a coin compartment in said cas-

ing having an open bottom overlying the slide member and in registry with said coin receiving opening when the slide member is disposed within the casing, said slide member including a bifurcated end, each furcation of said bifurcated end having a lateral projection, a swingable locking member in said casing overlying said slide member and engaging said projections to lock the slide member against sliding movement, electric means carried by said casing for raising the locking member away from the projection to permit sliding movement of the slide member, a switch connected to said electric means and including a pair of upper and lower elongated conductive members overlying and paralleling said slide member and disposed in said casing, one of said conductive members being secured to said casing, an insulated block joining said conductive members, and a switch operator member carried by and slidable transversely of the slide and underlying said lower conductive member for engaging and forcing the lower conductive member into circuit closing position with said upper conductive member, the bottom wall of said casing including a slot slidably receiving said switch operator member.
